United States Patent Office.

EDWARD HISERODT, OF WASHINGTON, ILLINOIS.

Letters Patent No. 63,048, dated March 19, 1867.

IMPROVED RAILROAD CROSSING.

The Schedule referred to in these Letters Patent and making part of the same.

TO ALL WHOM IT MAY CONCERN:

Be it known that I, EDWARD HISERODT, of Washington, in the county of Tazewell, and State of Illinois, have invented a new and improved Railroad Crossing; and I do hereby declare that the following is a full, clear, and exact description thereof, which will enable those skilled in the art to make and use the same, reference being had to the accompanying drawings, forming part of this specification, in which—

Figure 1 represents a plan or top view of my invention.

Figure 2, a side view of the same.

Similar letters of reference indicate corresponding parts.

This invention relates to a new and improved chair, constructed or cast as hereinafter shown and described, whereby two tracks are allowed to intersect each other at any angle, and the cars on one track allowed to cross the track of the other railroad without the movement or adjustment of any frogs or switches.

A represents the cast-iron crossing-chairs, one of which is used at each point where one rail crosses another, four being required where two single tracks cross each other. The base *a* of the chair casting, which rests upon the bed timbers *B*, extends transversely underneath the rail *C*, towards the centre of the track, of suitable thickness and width, as represented in the drawing, and of similar thickness and width outside of the rail, as shown in fig. 2, on the top of which a lip, *b*, is carried around the base of the rail, and upward under, and forming a support to, the tread *c* of the rail, to which the casting is fitted as nearly as practicable. No lip is cast to the chair on the inside of the rail, which admits of the substitution of new rails for the old, which may be worn out, merely by the removal of the bolts *d*, which confine them to the chairs. The small circular top projections *e*, on the lip on the outside of the chair, are cast upon the chair, with bolt holes through them horizontally, of suitable size; and the rails have corresponding holes punched or drilled through them, so that, when laid in their places, they are firmly bolted to the chairs. The chairs *A* are made of sufficient length to extend, at the proper angle of the crossing, nearly or quite to the centre of each track, as may be desired, (see fig. 1,) and also on each track outside of or beyond the crossing, as a chair to which to fasten the ends of the rails of the tracks, connecting with the crossing by bolts through the lips on the outside of the chair, with the proper openings *g* on the casting for the passage through of the flanges of the wheels when running over the crossing, the whole of the chairs being firmly bolted or spiked to the bed timbers beneath through bolt or spike holes cast in the base of the chair. The ends of the rails, it will be seen by referring to fig. 1, are firmly stayed by right-angular cleats *h*, cast on the upper surfaces of the chairs. Thus, by this simple arrangement, an economical crossing is obtained, and one which avoids the necessity of all movable frogs and switches.

I claim as new, and desire to secure by Letters Patent—

The peculiar form and arrangement of the crossing-chair, with the lip outside of the rail holding it to its position, with the omission of the lip on the inner side of the rail, and the application of the cleats *h*, as and for the purpose described.

EDWARD HISERODT.
